CLAIM

The ornamental design for a camera lens, as shown and described.

DESCRIPTION

FIG. 1 is a rear, top and right side perspective view of a camera lens showing our new design;

FIG. 2 is a front, bottom and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is an enlarged view showing a portion defined by lines 8-8 in FIG. 1; and,

FIG. 9 is an enlarged view showing a portion defined by lines 9-9 in FIG. 2.

The evenly-spaced broken lines illustrate portions of the camera lens in which the design is embodied that form no part of the claimed design. The dash-dotted broken lines denote the boundary of the claim and form no part of the claimed design.
